CONTAINER FOR TAPE REEL

Gregory Mathus, West Hartford, Conn., assignor to Morningstar Corporation, Cambridge, Mass., a corporation of Massachusetts

Filed Sept. 10, 1962, Ser. No. 71,609

Term of patent 14 years

(Cl. D58—11)

FIG. 1 is a top view of the container for tape reel, showing my new design;

FIG. 2 is a side view of the container for tape reel;

FIG. 3 is a bottom view of the container for tape reel; and

FIG. 4 is a cross-sectional view through the top element of the container for tape reel, taken along the section line 4—4 of FIG. 1.

I claim:

The ornamental design for a container for tape reel, as shown.
